UNITED STATES PATENT OFFICE.

JOSEPH L. BUCKLEY, OF TRENTON, NEW JERSEY, ASSIGNOR, BY MESNE ASSIGNMENTS,
TO PROCTOR & SWARTZ, INCORPORATED, OF PHILADELPHIA, PENNSYLVANIA, A
CORPORATION OF PENNSYLVANIA.

DRYING APPARATUS.

Application filed July 22, 1920. Serial No. 398,092.

This invention relates to an improvement in apparatus for drying or conditioning articles composed of clay, porcelain or the like, with the object in view of providing such an apparatus which occupies a minimum of floor space while being capable of rapidly and simultaneously drying a large number of articles.

Another object is to provide such an apparatus in which the articles to be dried may be progressively subjected to appropriate conditions of treatment and in appropriate positions, in order to produce a uniform product.

Another object is to provide such an apparatus in which the articles to be dried may be subjected to air currents impinging upon them from many different directions, during the course of their travel through the apparatus.

Another object consists in providing certain improvements in the form, construction and arrangement of the several parts whereby the above named and other objects may be effectively attained.

Practical embodiments of the invention are represented in the accompanying drawings, in which:

Fig. 1 represents a longitudinal vertical section through the apparatus.

Fig. 2 represents an end view of the same.

Fig. 3 represents a section taken in the plane of the line III—III of Fig. 1, looking in the direction of the arrows.

Fig. 4 represents a longitudinal vertical section through a modified form of apparatus.

Fig. 5 represents an end elevation of the apparatus shown in Fig. 4.

Fig. 6 represents a section taken in the plane of the line VI—VI of Fig. 4, looking in the direction of the arrows.

Referring to the preferred form shown in Figs. 1, 2 and 3, the apparatus includes a rectangular enclosure or housing 1.

This construction is conventionally shown in the drawings, but is fully described in my co-pending application, Serial No. 353,226, filed January 22, 1920. This construction is, generally considered, of standard form, but as set forth in said co-pending application, I prefer to make use of certain special features such as composing the inner surface of the plates which constitute the

walls of galvanized steel, in order to prevent rust and soldering all openings into the interior of the plates which may be made during the fitting of the parts, in order to prevent access of moisture to the insulating material.

The enclosure 1 is divided into two main sections 2 and 3 by means of a vertical partition 4 which abuts the top of the housing and extends down about $\frac{3}{4}$ of the way toward the bottom thereof. This partition is secured to and supported by the framework of the housing. As a result of this main division, I am enabled to provide substantial differences in the conditions of heat and moisture between the sections 2 and 3, so that the articles to be dried may be appropriately treated in each of the two sections.

The said sections are each sub-divided by means of other transverse partitions so as to include what I may call a diffusing chamber, a vertical channel, a horizontal channel and a vertical duct. These last named partitions consist of a vertical partition 5, vertical partition 6, horizontal partition 7 and slanting partition 8. Each of these partitions extends from side to side of the enclosure and is suitably secured to and held in position by the framework of the enclosure. The partition 5 is perforated so as to be of grate-like formation, while the partitions 6, 7 and 8 are solid. The partition 6 is composed of thermo-insulated plates similar to those described as being employed in the construction of the housing 1. The diffusing chamber mentioned is denoted by 9 and is bounded by the partitions 5, 7, 8 and the fan to be hereinafter described. The horizontal channel is marked 10 and is bounded by the partition 7 and the bottom of the casing 1. The vertical channel is indicated by 11 and is defined by the partitions 4 and 5. The duct is marked 12 and is defined by the partitions 6 and 8 and the fan.

The parts just mentioned are embodied in the section 2 and, as already indicated, the section 3 is quite similarly constructed. It has a vertical grated partition 13 which is arranged and supported in the same manner as the partition 5; a partition 14 which corresponds to the partition 7 and a partition 15 which substantially corresponds to the partition 8. However, this partition 15 is somewhat longer than the partition 8 and is

- interrupted centrally by an aperture 16 for permitting the passage of the trays conveying the articles to be dried, as will be hereinafter described. Furthermore this section 3 has no partition that corresponds to the partition 6. In the section 3 the diffusing chamber is bounded by the partitions 13, 14, 15 and a second fan to be hereinafter described, and this chamber is marked 17. The horizontal channel is denoted by 18 and is bounded by the partition 14 and bottom of the housing 1. The vertical channel is indicated by 19 and is defined by the partitions 4 and 13. The vertical duct is denoted by 20 and is bounded by the partition 15, the adjacent end of the housing 1, and the said last named fan.
- Means is provided for generating an air current within each of the sections 2 and 3 and, referring to the section 2, this means consists of a fan 21 that is mounted on a shaft 22 which is journaled in a bearing 23 secured to the partition 6. The other end of the shaft 22 carries a bevel gear 24 which mates with a similar gear 25 that is fixed on the end of a cross shaft 26 which extends laterally to the exterior of the housing 1 and is provided on its outer end with a belt pulley 27 designed to be driven from a suitable source of power, not shown. The fan 21 is surrounded by a circular guard or shield 28 which is supported by the partition 8 and a horizontally disposed transverse plate 29 which extends from side to side of the housing 1 and abuts the top of the partition 6. This plate 29 also extends to the adjacent end of the housing 1 except that it is interrupted by an aperture 30 which permits the passage of the trays carrying the articles to be dried therethrough. The bottom of the partition 6 is bent so as to lie parallel with the partition 8 and is also connected to a horizontally disposed transverse plate 31, which extends to the adjacent end wall of the housing 1 with the exception that it is interrupted by an aperture 32 which, like the aperture 30, is designed to permit the passage of the trays carrying the articles to be dried.
- Referring to the section 3; the fan is indicated by 33 and is mounted on a shaft 34 which is journaled in a bearing 35 fixed to the adjacent end of the housing. The shaft 35 carries a bevel gear 36 which mates with a similar gear 37 secured to the end of a transverse shaft 38 which carries a belt pulley 39 on its other end so that it may be driven from a suitable source of power, not shown.
- As a result of the structure just described, it will be seen that the fans 21 and 33 will, when driven, provide currents of air within the housing 1, and the course and effect of these currents will be hereinafter more fully described.

Means is included for heating the air currents, and this means consists of radiators which are located within the diffusing chambers 9 and 17. These radiators are transversely disposed with respect to the housing 1 and are arranged in staggered vertical relation. The radiators in the chamber 9 are denoted by 40, 41, 42, 43 and 44. They are all of substantially the same capacity and spaced substantially equal distances apart. In the chamber 17 the radiators are marked 45, 46, 47, 48, 49 and 50. These radiators are spaced substantially equal distances apart, but it will be noted that radiators 46, 47 and 48 are substantially twice as large as radiators 40 to 45 inclusive, and that radiators 49 and 50 are substantially three times as large as radiators 40 to 45 inclusive. As a result of this arrangement, it will be clear that the capacity for heating the chamber 17 is much greater than that for heating the chamber 9 and that it is possible to gradually and greatly increase the heat supply to the chamber 17 as the location of the fan therein is approached. Thus, the articles to be dried may be progressively subjected to a hotter and drier air as they advance through the housing.

These radiators are preferably composed of cast iron in order to eliminate rusting and may be supported by the angle iron framework of the housing. I prefer to equip each radiator with its own controlling means so as to be able to regulate the supply of steam to each independently of the others, for the purpose of varying the temperature of the different radiators as desired. Such controlling means may be of any well known or approved form; and, as they are well understood by those acquainted with this art, no illustration or description is necessary.

The apparatus also includes means for progressively transporting the articles to be dried through the enclosure, and this means comprises two sets of sprocket wheels, each set being mounted adjacent one side wall of the housing 1. One set of these sprockets is diagrammatically represented in Fig. 1, and the sprockets are indicated by 51, 52, 53, 54, 55, 56, 57, 58, 59, 60, 61, 62, 63 and 64. It will be understood that the other set of sprockets is exactly like that just described and that the members of the said other set are mounted in axial alinement with the members of the first set, each corresponding pair of members in the two sets being mounted on shafts that are journaled in the framing of the sides of the housing. These shafts are denoted by 65, 66, 67, 68, 69, 70, 71, 72, 73, 74, 75, 76, 77 and 78. Endless sprocket chains, one of which is marked 79, pass around each set of the said sprockets as represented, chiefly diagrammatically, in Fig. 1, and the trays 80 which immediately

support the articles to be dried have their end members pivoted to the links of the sprocket chains, as indicated at 81, so that the trays will be suspended from the chains under the influence of gravity.

Mechanism is provided for actuating the chains so as to convey the trays through the enclosure, which mechanism is engaged with the shaft carrying the sprocket 62 and consists of a worm wheel 82 fixed to said shaft 76, which worm wheel meshes with a worm 83 that is connected by a suitable train of shafts and gearing with a belt pulley 84 that is to be driven from a suitable source of power, not shown. It will be noted that the drive for the said chains which carry the trays is separate from the drives for the fans, so that the latter may be continued in operation even though the chains and hence trays are motionless. This feature is desirable since, if the circulation of air were stopped when the chains were motionless, the articles which happened to be adjacent one of the radiators would be apt to be injured by the excessive heat.

The housing 1 is provided with a suitable loading and unloading aperture 85, through which the articles to be dried may be placed on the trays 80 and, removed from the said trays, after they have passed through the apparatus. The partition 6 is composed of thermo-insulated material already described, so as to prevent the escape of the hot air through the opening 85, which escape, if it occurred, would interfere with the work of the attendant as well as decrease the economy of the apparatus.

In operation, heat will be supplied to the radiators 40 to 50 inclusive, and the fans 21 and 33 and chains 79 and its mate set in operation. The articles to be dried are now placed upon the trays 80 as the latter slowly pass the feed opening 85. As the articles pass up between the partition 6 and the adjacent end wall of the housing 1, it will be noted that they are out of contact with the heated air current, since they are shielded by the said partition. Nevertheless, they are subjected to a certain elevated temperature which serves to initiate the drying operation. As the articles pass the sprockets 51 and 52, they reach a more elevated temperature and as they pass downwardly from the sprocket 52 to the sprocket 53, they begin to be acted upon by the heated air current generated by the fan 21 and heated by the radiator 40. This air current impinges against the articles substantially in a horizontal direction, although the air is somewhat broken up by passing through the radiator 40 so as to attack the articles at slightly different angles. After the articles have rounded the sprocket 53 and begin their travel upwardly toward the sprocket 54, they continue to be subjected to a similar air

current except that the current is somewhat warmer because it has passed through the radiator 41 as well as the radiator 40, and is somewhat more diffused because it has been broken up by the pipes of both said radiators. The downward travel of the articles from the sprocket 54 to the sprocket 55 causes them to be subjected to similar but stronger influences and the same is true of their upward passage from sprocket 55 to sprocket 56. After rounding the latter and starting through the vertical channel 11, toward the sprocket 57, the articles are subjected to a still hotter air current owing to its passage through the radiator 44 and the air is much more diffused and its direction of impingement against the articles very much diversified because of its being broken up by the grate-like partition 5. Moreover the partition 4 obstructs the lateral movement of the air current and directs it downwardly so that it engages the articles while moving in the same direction as that in which they are traveling.

After the articles have passed the sprocket 57 and start to ascend in the duct 19 they are subjected to heated and diffused air currents generated by the fan 33 and moving laterally or horizontally, as well as by part of the said air currents generated by the said fan which impinge against the partition 4 and are turned downwardly so as to contact with the articles while moving oppositely thereto but in a similar path. During the travel from the sprocket 58 to the sprocket 59, the articles are subjected to still greater heat because of the size of the radiator 46, and this heat is increased during each successive stage of travel from sprocket to sprocket until the highest temperature is reached while the articles are moving downwardly between the radiators 49 and 50. After passing between the last-named radiators, the articles travel through the opening 16 and enter the horizontal channel 18 through which they pass and immediately enter and pass through the horizontal channel 10. While passing through the channel 18, it will be seen that the articles are engaged by an air current, generated by both fans, which moves in the direction opposite to the travel of the articles. In the channel 10 the articles are attacked by air currents, generated by both fans, which move in the same direction as the articles. Upon reaching the end of the channel 10 the articles pass up through the opening 32 and may be removed by the operator through the door or aperture 85.

I wish to call attention to the fact that, at the time the articles are rounding the sprocket 57, they are subjected to a number of different air currents, that is, to air currents moving in a number of different directions, which directions include vertical move-

- ment and horizontal movement in opposite directions. This is a feature of importance in that this condition insures complete contact of the air with all parts of the articles.
- 5 Furthermore, when the articles move into the chamber 3, the air current which acts upon them is driven in a direction opposite from the current in the chamber 2, so that the direct effect of the air is upon the side of 10 the articles opposite to that which the air directly engages in the chamber 2. As will be seen from the arrows, Fig. 1, the air current generated by the fan in each chamber follows an elliptical course moving outwardly from the fan, downwardly through the vertical channel 11 or 19, as the case may be, backwardly through the horizontal channel 10 or 18, as the case may be, and returning to the fan through the duct 12 or 20, as 15 the case may be.

Upon the return run of the articles through the horizontal channels 18 and 10, they are not subjected to such intense conditions of heat and air current, so that there is 20 opportunity for them to return somewhat toward normal atmospheric conditions before leaving the apparatus. This is desirable as it avoids a sudden change in the conditions 25 affecting the articles.

30 Referring to the modified form shown in Figs. 4 to 6 inclusive, it will be observed that the general arrangement is substantially the same as that of the preferred form. One of the chief distinctions resides in the fact that 35 this modified form of apparatus is designed to occupy two floors or stories of a building so that it may, if desired, be loaded from an upper floor and unloaded on a lower floor. This is frequently a material advantage in 40 that the upper floor of a building may be adapted to the production of the articles up to the stage at which they should enter the drying apparatus, and the lower floor used for the treatment of the articles after they 45 have passed through the apparatus. This also serves to convey the articles from the one floor to the other, thus obviating the necessity of extra transportation means.

50 In this form the intermediate floor is denoted by 86. The housing is marked 87, and includes the two sections 88 and 89 divided by the partition 90. The two diffusing chambers are marked 91, 92, and are defined by partitions 93, 94, 95, 96, 97, 98, the fans 99 and 100 and partitions 101, 102. The 55 partitions 93 and 94 are of grated formation like the partitions 5 and 13 in the preferred form. The vertical channels are marked 103, 104, and the horizontal channels 105, 106.

60 The ducts are 107 and 108. Insulated partitions 109, 110, are arranged at each end, and are similar in function to the partition 6 in the preferred form. The housing has 65 four openings 111, 112, 113, 114, so that it may be loaded and unloaded on either floor and

at either end. The two insulated partitions 109, 110, serve to protect the operators at any of the loading and unloading openings.

The radiators in chamber 91 are marked 115, 116, 117, 118 and 119; and those in chamber 92 are denoted by 120, 121, 122, 123, and 124. One set of sprockets is represented by 125, 126, 127, 128, 129, 130, 131, 132, 133, 134, 135, 136, 137, 138 and 139. These sprockets are mounted on shafts 140, 141, 142, 143, 144, 145, 146, 147, 148, 149, 150, 151, 152, 153, and 154. It will be understood that the other set of sprockets is exactly like that just described and that the sprockets composing it are mounted on the shafts just mentioned; each set of sprockets being adjacent a side wall of the housing as is the case in the preferred form.

The means for driving the fan 99 is indicated generally by 155 and the means for driving the fan 100 by 156. These means are similar to those shown in the preferred form. The sprocket chains, one of which is represented by 157, are driven by a means similar to that employed in the preferred form, 90 which means is denoted generally by 158. The trays are marked 159.

It will be observed that the ends of the housing 87 are elevated above the central portion thereof, and this is done in order to 95 accommodate the sprockets 125 and 137 which are so located as to properly guide the chains between the partitions 109, 110, and the adjacent ends of the housing. The apertures through which the chains pass in 100 their last named travel are marked 160, 161, 162 and 163.

The method of operation of this form is substantially the same as that described in connection with the preferred form and will 105 doubtless be understood without repetition. It may simply be remarked that the articles may be loaded and unloaded through any one of the openings 111, 112, 113 and 114, according as the conditions of treatment may 110 be desired to be varied.

In reference to all the forms, it will be observed that the diameter of all the sprockets, except those at the ends of the horizontal channel or channels, is greater than the distance between the two sprockets which are immediately connected with the sprocket in question by the chain. Hence the sections of travel of the chain between the sprockets are at a slight angle to the vertical so as to 115 cause an angular contact of even the vertically moving currents with the articles. In other words, at no stage of the travel of the articles, do the trays completely protect 120 them from the air current.

125 It will be understood that various changes may be resorted to in the form, construction and arrangement of the several parts without departing from the spirit and scope of the invention and hence I do not intend to 130

be limited to the details herein shown and described except as they may be included in the claims.

What I claim is:

5. 1. Apparatus of the character described comprising, an enclosure, and carrier means for transporting articles to be dried from end to end of said enclosure, the enclosure having an upper and lower loading and unloading openings, whereby the articles may be placed on the carrier from an elevated position and removed therefrom at a lower position. 70
10. 2. Apparatus of the character described comprising, an enclosure; and carrier means for transporting articles to be dried from end to end of said enclosure, the enclosure having a pair of loading and unloading openings at each end in the upper and lower portions thereof, whereby the articles may be loaded or unloaded at either end of the closure and at an elevated or a lowered position. 75
15. 3. Apparatus of the character described comprising, an enclosure, a vertical transverse partition located substantially centrally thereof for dividing the enclosure into two sections while permitting communication between said sections, a horizontal partition in each section spaced from the bottom of the enclosure, and means in each section for generating air currents in opposite directions substantially parallel with the horizontal partitions and against the vertical partition. 80
20. 4. Apparatus of the character described comprising, an enclosure, a vertical transverse partition located substantially centrally thereof and spaced from the bottom of the enclosure for dividing the enclosure into two sections while permitting communication between said sections, a horizontal partition in each section spaced from the bottom of the enclosure and located below the bottom of the vertical partition, and means in each section for generating air currents in opposite directions substantially parallel with the horizontal partitions and against the vertical partition. 85
25. 5. Apparatus of the character described comprising, an enclosure, a vertical transverse partition located substantially centrally thereof and abutting the top and spaced from the bottom of the enclosure for dividing the enclosure into two sections while permitting communication between said sections, a horizontal partition in each section spaced from the bottom of the enclosure and located below the bottom of the vertical partition, and means in each section for generating air currents in opposite directions substantially parallel with the horizontal partitions and against the vertical partition. 90
30. 6. Apparatus of the character described comprising, an enclosure, a vertical transverse partition located substantially centrally thereof and spaced from the bottom of the enclosure for dividing the enclosure into two sections while permitting communication between said sections, a vertical transverse partition located in each section and spaced from said first named partition, a horizontal partition in each section spaced from the bottom of the enclosure, and means in each section for generating air currents in opposite directions substantially parallel with the horizontal partitions and against the vertical partition. 95
35. 7. Apparatus of the character described comprising, an enclosure, a vertical transverse partition located substantially centrally thereof and spaced from the bottom of the enclosure for dividing the enclosure into two sections while permitting communication between said sections, a vertical transverse partition located in each section and spaced from said first named partition, said graded partitions being spaced from the bottom of the enclosure but extending below the bottom of said first named partition, a horizontal partition in each section spaced from the bottom of the enclosure, and means in each section for generating air currents in opposite directions substantially parallel with the horizontal partitions and against the vertical partition. 100
40. 8. Apparatus of the character described comprising, an enclosure, a vertical transverse partition located substantially centrally thereof and spaced from the bottom of the enclosure for dividing the enclosure into two sections while permitting communication between said sections, a horizontal partition in each section spaced from the bottom of the enclosure and located below the bottom of the vertical partition, a vertical transverse partition located in each section and spaced from said first named partition, said graded partitions being connected with said horizontal partitions, and means in each section for generating air currents in opposite directions substantially parallel with the horizontal partitions and against said graded and first named partitions. 105
45. 9. Apparatus of the character described comprising, an enclosure, a vertical transverse partition located substantially centrally thereof and spaced from the bottom of the enclosure for dividing the enclosure into two sections while permitting communication between said sections, a horizontal partition in each section spaced from the bottom of the enclosure and located below the bottom of the vertical partition, a vertical transverse partition located in each section and spaced from said first named partition and from the top of the 110
50. 10. 5. Apparatus of the character described comprising, an enclosure, a vertical transverse partition located substantially centrally thereof and abutting the top and spaced from the bottom of the enclosure for dividing the enclosure into two sections while permitting communication between said sections, a horizontal partition in each section spaced from the bottom of the enclosure and located below the bottom of the vertical partition, and means in each section for generating air currents in opposite directions substantially parallel with the horizontal partitions and against the vertical partition. 115
55. 6. Apparatus of the character described comprising, an enclosure, a vertical transverse partition located substantially centrally thereof and spaced from the bottom of the enclosure for dividing the enclosure into two sections while permitting communication between said sections, a horizontal partition in each section spaced from the bottom of the enclosure and located below the bottom of the vertical partition, and means in each section for generating air currents in opposite directions substantially parallel with the horizontal partitions and against the vertical partition. 120
60. 7. Apparatus of the character described comprising, an enclosure, a vertical transverse partition located substantially centrally thereof and spaced from the bottom of the enclosure for dividing the enclosure into two sections while permitting communication between said sections, a horizontal partition in each section spaced from the bottom of the enclosure and located below the bottom of the vertical partition, a vertical transverse partition located in each section and spaced from said first named partition and from the top of the 125
65. 8. Apparatus of the character described comprising, an enclosure, a vertical transverse partition located substantially centrally thereof and abutting the top and spaced from the bottom of the enclosure for dividing the enclosure into two sections while permitting communication between said sections, a horizontal partition in each section spaced from the bottom of the enclosure and located below the bottom of the vertical partition, and means in each section for generating air currents in opposite directions substantially parallel with the horizontal partitions and against the vertical partition. 130

enclosure, and means in each section for generating air currents in opposite directions substantially parallel with the horizontal partitions and against said grated 5 and first named partitions.

10. Apparatus of the character described comprising, an enclosure, a vertical transverse partition located substantially centrally thereof and spaced from the bottom 10 of the enclosure for dividing the enclosure into two sections while permitting communication between said sections, a horizontal partition in each section spaced from the bottom of the enclosure and located below 15 the bottom of the vertical partition, a vertical transverse grated partition located in each section and spaced from said first named partition, said grated partitions being spaced from the top of the enclosure 20 and connected with said horizontal partitions, and means in each section for generating air currents in opposite directions substantially parallel with the horizontal partitions and against said grated and first 25 named partitions.

11. Apparatus of the character described comprising, an enclosure, a vertical transverse partition located substantially centrally thereof for dividing the enclosure into 30 two sections while permitting communication between said sections, a horizontal par-

tition in each section spaced from the bottom of the enclosure, means in each section for generating air currents in opposite directions substantially parallel with the horizontal partitions and against the vertical partition, carrier means for transporting the articles to be dried from end to end of said enclosure, said enclosure having loading and unloading openings in the ends thereof, and 35 insulated transverse partitions located adjacent said ends of the enclosure for protecting said openings and providing protected passageways for the carrier means while the articles are being loaded thereon and un- 40 loaded therefrom. 45

12. Apparatus of the character described comprising, an enclosure, carrier means for transporting articles to be dried from end to end thereof, and said enclosure having 50 loading and unloading openings in the ends thereof, the end portions of the enclosure being elevated for receiving elements of said carrier means in order to provide an extended travel of the carrier means adjacent 55 the ends of the enclosure to facilitate the loading and unloading of the articles.

In testimony, that I claim the foregoing as my invention, I have signed my name, this nineteenth day of July nineteen hundred 60 and twenty.

JOSEPH L. BUCKLEY.

enclosure, and means in each section for generating air currents in opposite directions substantially parallel with the horizontal partitions and against said grated 5 and first named partitions.

10. Apparatus of the character described comprising, an enclosure, a vertical transverse partition located substantially centrally thereof and spaced from the bottom 10 of the enclosure for dividing the enclosure into two sections while permitting communication between said sections, a horizontal partition in each section spaced from the bottom of the enclosure and located below 15 the bottom of the vertical partition, a vertical transverse grated partition located in each section and spaced from said first named partition, said grated partitions being spaced from the top of the enclosure 20 and connected with said horizontal partitions, and means in each section for generating air currents in opposite directions substantially parallel with the horizontal partitions and against said grated and first 25 named partitions.

11. Apparatus of the character described comprising, an enclosure, a vertical transverse partition located substantially centrally thereof for dividing the enclosure into 30 two sections while permitting communication between said sections, a horizontal par-

tion in each section spaced from the bottom of the enclosure, means in each section for generating air currents in opposite directions substantially parallel with the horizontal partitions and against the vertical partition, carrier means for transporting the articles to be dried from end to end of said enclosure, said enclosure having loading and unloading openings in the ends thereof, and 35 insulated transverse partitions located adjacent said ends of the enclosure for protecting said openings and providing protected passageways for the carrier means while the articles are being loaded thereon and un- 40 loaded therefrom.

12. Apparatus of the character described comprising, an enclosure, carrier means for transporting articles to be dried from end to end thereof, and said enclosure having 45 loading and unloading openings in the ends thereof, the end portions of the enclosure being elevated for receiving elements of said carrier means in order to provide an extended travel of the carrier means adjacent 50 the ends of the enclosure to facilitate the loading and unloading of the articles.

In testimony, that I claim the foregoing as my invention, I have signed my name, this nineteenth day of July nineteen hundred 55 and twenty.

JOSEPH L. BUCKLEY.

CERTIFICATE OF CORRECTION.

Patent No. 1,618,913.

Granted February 22, 1927, to

JOSEPH L. BUCKLEY.

It is hereby certified that the name of the assignee in the above numbered patent was erroneously written and printed "Proctor & Swartz, Incorporated", whereas said name should have been written and printed as "Proctor & Schwartz, Incorporated", as shown by the records of assignments in this office; and that the said Letters Patent should be read with this correction therein that the same may conform to the record of the case in the Patent Office.

Signed and sealed this 4th day of October, A. D. 1927.

Seal.

M. J. Moore,
Acting Commissioner of Patents.
